UNITED STATES PATENT OFFICE.

JOSEPH J. KULAGE, OF ST. LOUIS, MISSOURI.

BRICK-MACHINE.

SPECIFICATION forming part of Letters Patent No. 516,376, dated March 13, 1894.

Application filed January 9, 1891. Serial No. 377,299. (No model.)

To all whom it may concern:

Be it known that I, JOSEPH J. KULAGE, of St. Louis, Missouri, have made a new and useful Improvement in Brick-Machines, of which 5 the following is a full, clear, and exact description.

The present improved machine is a comparatively simple, compact, and powerful brick-press designed more especially for the 10 pressing into bricks of dry and partially dry clay, and particularly those clays which are poor in cohesive qualities, and also for repressing mud and other bricks which have previously been molded or made either by hand 15 or machine.

To this end the improvement consists mainly in the means whereby the full pressure of the machine is brought to bear upon the clay or bricks in the mold and then maintained thereon for a prolonged period, substantially as is hereinafter described and claimed, 20 aided by the annexed drawings, making part of this specification, in which—

Figure 1 is a side elevation of the improved 25 machine; Fig. 2 a side elevation of the cam-shafts and cams; Fig. 3 a section on the line 3—3 of Fig. 2; Fig. 4 a vertical, transverse section of the machine on the line 4—4 of Fig. 1; and Fig. 5 a vertical, longitudinal section on the line 5—5 of Fig. 4.

The same letters of reference denote the same parts.

Only those portions of the construction which are essential to an understanding of 35 its improved features are exhibited in the drawings.

The present machine belongs to that class of brick-machines in which upper and lower 40 plungers are used.

The mold or molds are represented at A, and B represents the lower plunger, and C 45 represents the upper plunger.

D represents a shaft, journaled in bearings 50 d, d, in the frame-work, E, of the machine, and provided with three cams, namely a central cam, F, which actuates the upper plunger, and two cams G, G', at the sides respectively, of the central cam, which actuate the lower 55 plunger. In the revolution of the cam-shaft, D, the cam F acts to raise, and also to depress the upper plunger C, and the other cams, G, G', serve only to lift the lower plunger B.

To this end the upper plunger is attached to a slotted head, C', in the slot, c, of which the cam F works, the cam in its rotation bearing alternately upon some part of the head to raise it, and then upon some other part of the head to depress it. Said parts preferably take the form of friction-rollers, c', c², extending across the slot c and journaled in the head C' at the sides 60 respectively of the slot, and substantially as shown. The motion of the other cams, G, G', is communicated to the lower plunger as follows: The lower plunger is attached to, or forms part of, a cross-head, B', which, by means of rods H, H, is connected with an upper cross-head, I, having the friction-rollers i, i. The cams G, G', in their rotation encounter and uplift the rollers i, i, and the upper cross-head, the rods, the lower cross-head, and the 65 lower plungers are thereby raised. When the cams, G, G', have passed the rollers i, i, the lower plunger, and the parts connected therewith as described, fall. Any other suitable means for communicating the motion of the 70 cams G, G', to the lower plunger, for the purpose described, can be employed.

Motion is imparted to the cam-shaft preferably as follows: The cam shaft is provided with a gear wheel J, which engages with a 80 pinion K on a shaft k. This last named shaft is journaled in bearings k', k', and it is provided also with a gear wheel, k², which engages with a pinion, L, upon the driving shaft l having the fast and loose pulleys, l', l². The motion of the cam shaft and cams is indicated by the arrow x, Fig. 5. The shape and arrangement of the cams is a leading 85 feature of the construction. The cam, F, considered generally, is of a quadrantal shape, but, more particularly described, as follows: Commencing at the point f, at the inner end of its face, f', the cam extends in a semi-circular form to the point f²; the cam then curves farther around, but gradually enlarges 90 until the point, f³, is reached: this last named point is at the throw of the cam; from this point the cam curves around with the same radius, through an arc of about ninety degrees, to meet the face of the cam. The throw 95 of the cam is suited to the desired stroke of the upper plunger, and the length of the arc, f⁴, of the cam is proportioned to the length of the period during which the pressure is to be 100.

maintained upon the contents of the molds. The shape and the relative arrangement of the similar cams G, G', is as follows: The face, g, of these cams is about opposite the 5 point f^3 of the cam F, and beginning at the point g' , at the inner end of the face g, the cams curve around, and at the same time gradually enlarge in diameter, throughout an arc somewhat greater than a semi-circle and 10 until the point g^2 is reached; from this point on the backs of the cam extend in a tangential direction until the point g^3 , is reached, from this last named point the backs of the 15 cams extend in a circular arc, g^4 , until the face of the cam is reached; the relative position of the cam F and the cams G, G', is substantially indicated in Figs. 2, 3, and 5.

The operation is as follows: In Figs. 4 and 20 5 the position of the parts is as when both of the plungers have been raised to the upper limits of their respective strokes, and the recharging of the molds is about to be accomplished: the cams G, G', now pass the rollers 25 i , i , and the lower plunger in consequence falls to the bottom of the molds, making room for the new charge: the upper plunger must be upheld until the charging of the molds is effected: this is accomplished by means of the portion, f^4 , of the cam F, the upper plunger 30 being upheld until the face, f^1 , of that cam passes the roller c' ; the upper plunger is now no longer upheld and it drops until it rests upon the contents of the molds: at or 35 about this point of time the point f^2 of the cam F has come to a bearing upon the lower friction-roller c^2 , and the pressure upon the contents of the molds has been initiated: the pressure continues to increase until the point f^3 of the cam comes to bear upon the roller 40 c^2 : the maximum pressure of the press is now obtained, and such maximum pressure is retained upon the contents of the molds until the portion f^4 of the cam has passed the roller

c^2 , whereupon, in the rotation of the cam shafts and cams, the operation is repeated. 45

The mechanism for operating the charger, M, being well understood, is not illustrated. The fall of the lower plunger in the molds is regulated preferably by means of the wedge N. The wedge engages with the horizontally 50 arranged, threaded stem n, which is held and adapted to rotate in a bearing n' , in the framework E. The lower cross-head is beveled at b, to coact with the wedge.

In carrying out this improvement I desire 55 not to be restricted to brick-machines, as a press containing the improvement is adaptable for compressing various substances into various forms, and for various purposes. The improved machine is desirable for its simplicity, compactness and strength. The cams are all on one shaft: the pressure is obtained without the use of toggles or levers: a single shaft suffices for operating both lower and upper plungers: the cams can be integral 60 with the shaft; the pressure can be maintained upon the contents of the molds as long as desired: the cam shaft and cams are above the mold-table and thus out of the way largely of any dirt: and the cam shaft is not subjected to a twisting strain. 70

I claim—

The combination in a press as described, of the molds, the cross heads and their connecting rods, and rollers in the upper cross head, 75 the cam shaft D, having thereon the central cam F, and the side cams G, G', the plunger C, raised and lowered by said cam F, and the plunger B, operated by the cams G, G', all substantially as and for the purposes set 80 forth.

Witness my hand December 31, 1890.

JOSEPH J. KULAGE.
